G. L. HUDSON.

DOOR SPRING.

No. 22,874.

PATENTED FEB. 8, 1859.

ONLY DRAWING ACCESSIBLE
TAKEN FROM PATENT OFFICE REPORT
1859 - VOL. II -

UNITED STATES PATENT OFFICE.

GILBERT L. HUDSON, OF CONNEAUT, OHIO.

DOOR-SPRING.

Specification of Letters Patent No. 22,874, dated February 8, 1859.

To all whom it may concern:

Be it known that I, GILBERT L. HUDSON, of Conneaut, in the county of Ashtabula and State of Ohio, have invented, contrived, devised, and arranged a new and Improved Plan, Mode, Form, or Combination to Use as a Gate and Door Closer; and I do hereby declare that the following is a full and exact description thereof, as near as I can describe.

10 The nature of my invention, contrivance, device, and arrangement as a useful improvement for a gate and door closer, comprises and consists in (as designated on my drawings) a standard letter A, coil spring 15 B, stirrup C, crotch lever D, connecting wire F, and the connecting link F, to the gate or door G.

I do not claim any of the described parts separately, or in detail, but

I do claim as my invention or device, and 20 original with me—

The use of the standard A, coil spring B, stirrup C, crotch lever D, connected with rod F, link F, as operating vice versa to gate or door G, the whole as arranged or connected, and operating substantially in the 25 manner and for the purpose set forth.

G. L. HUDSON.
